STANLEY G. NOTTAGE, OF WILKINSBURG, PENNSYLVANIA, ASSIGNOR TO WESTINGHOUSE ELECTRIC AND MANUFACTURING COMPANY, A CORPORATION OF PENNSYLVANIA.

SYSTEM OF CONTROL.

1,294,147.

Specification of Letters Patent. Patented Feb. 11, 1919.

Application filed February 10, 1916. Serial No. 77,431.

To all whom it may concern:

Be it known that I, STANLEY G. NOTTAGE, a subject of the King of Great Britain, and a resident of Wilkinsburg, in the county of 5 Allegheny and State of Pennsylvania, have invented a new and useful Improvement in Systems of Control, of which the following is a specification.

My invention relates to systems of control 10 and especially to the acceleration and phase-regulation of induction motors and the like.

One object of my invention is to provide a novel method and means of the above-indicated character whereby an induction 15 motor or set of induction motors may be operated in conjunction with speed-regulating means and phase-regulating means to produce a system that is relatively efficient and that has other desirable operating characteristics.

More specifically stated, it is an object of my invention to provide a method and system of the class under consideration wherein in a polyphase, variable resistor of relatively 25 low-starting-voltage characteristics is employed in connection with a certain arrangement of the secondary phase windings to effect motor acceleration and wherein a phase-advancing machine of relatively high- 30 running-voltage characteristics is subsequently employed for the usual purpose after the phase-windings have been re-arranged to produce a higher-voltage combination under the new conditions.

Another object of my invention is to provide a relatively simple and effective system of the above-mentioned type for permitting the concurrent use of speed-regulating means, such as variable resistors, and phase-regulating means, such as machines of the Leblanc 40 type, in the operation of induction motors.

Heretofore, in connection with the operation of induction motors for propelling electric railway vehicles, for example, when liquid rheostats have been employed for accelerating purposes and phase-advancing machines have been subsequently employed for compensating for the phase distortion that is caused by varying loads, certain limitations have been imposed upon the designer 50 of the apparatus by reason of predetermined inherent structural and operating characteristics of the liquid rheostat and the phase-advancing machine. Liquid rheostats, in the present state of development, are most

economically designed for maximum-starting-voltage operation of 700 to 800 volts, so that, when the induction motor is accelerated to full-speed conditions, a relatively low slip or running voltage will obtain in the secondary winding, thereby necessitating a relatively heavy current when the motors have a large capacity requirement. On the other hand, phase-advancing machines of the Leblanc type, for example, inherently operate 60 to better advantage under relatively low-current and corresponding high-running-voltage conditions. It should be borne in mind that the above-mentioned "high-running voltage" will not be likely to exceed 70 thirty or forty volts in machines of the prior art, but, nevertheless, a doubling or other increase of such voltage as is provided in my present invention will effect a material decrease of current, amounting in some cases 75 to several hundred amperes. As will be understood by those skilled in the art, the construction of polyphase commutator machine for the low-voltage, high-current operation that has been necessary in the past, is 80 unavoidably expensive and difficult.

According to my present invention, I provide an induction motor having its independent secondary phase-windings initially connected in a low-voltage combination, such 85 as delta relation of, or parallel relation of sections of, the respective phase-windings, and I accelerate the motor to full-speed conditions in conjunction with a liquid rheostat, whereby the necessary low-starting-voltage, 90 high-current characteristics are complied with; while, after the phase-windings have been short-circuited, which, of course, can be effected under full-speed conditions without any injurious or undesirable results such 95 as current surges or sudden changes of locomotive draw-bar pull, the phase-windings are reconnected in a higher-voltage combination, such as star-relation, and a phase-advancing machine having relatively high- 100 running-voltage, low-current characteristics is employed for the usual regulating purposes. In order to permit the use of as many conductors from the secondary phase-windings as is necessary, without requiring 105 slip rings, which are relatively expensive and occupy valuable space in a locomotive, I make the primary winding of the induction motor the rotor, whereby only a relatively small number of slip rings is necessary, and 110

I make the secondary phase-windings stationary. Thus, the operation of the induction motor is effected in accordance with the required operating characteristics of the 5 liquid rheostat and the phase-advancing machine in a relatively simple and reliable manner, as hereinafter more fully set forth.

My invention may best be understood by reference to the accompanying drawings, 10 wherein Figure 1 is a diagrammatic view of a system of control embodying my invention; Fig. 2 is a sequence chart of well-known form for indicating the preferred operation of the various switching devices 15 that are shown in Fig. 1; and Fig. 3 and Fig. 4, and Fig. 5 and Fig. 6, are views that correspond, respectively, to Fig. 1 and Fig. 2, of modifications of my invention.

Referring to Fig. 1 of the drawings, the 20 system shown comprises a plurality of suitable three-phase supply-circuit conductors A, B and C; an induction motor having a rotatable primary winding P and a stationary set of secondary phase-windings S; a 25 variable accelerating resistor, such as a liquid rheostat LR; a suitable phase-advancing means PA; and a plurality of suitable sets of switching devices 1, 2 and 3, respectively.

The rotatable primary winding P is preferably disposed upon the usual type of rotor structure and is provided with a plurality of slip rings R1, R2 and R3 upon which bear brushes 4, 5 and 6 that are respectively connected to the supply-circuit conductors 35 A, B and C through suitable conducting means 7, 8 and 9. The secondary stationary element S of the motor comprises a plurality of phase windings Sa, Sb and Sc that are independent the one of the other when the 40 sets of switches 2 and 3 are opened, are connected in delta relation upon the closure of switches 2 and in star relation upon the closure of switches 3, the phase-advancer PA forming the star-point of the system, as set forth in detail later.

The liquid rheostat LR may be of any suitable and familiar type, comprising an electrolyte-containing tank or vessel 10, within which are disposed appropriate immersible electrodes or plates 15 that are respectively connected, through conductors 16, 17 and 18, to the corresponding terminals 19, 20 and 25 of the secondary phase-windings Sb, Sc and Sa.

55 The phase-advancing machine PA may be of the familiar Leblanc or any other suitable type, and, as shown here, embodies a rotatable armature and a plurality of suitably spaced brushes 27, 28 and 29 that bear upon 60 the commutator cylinder 26 of the phase-advancer armature. Upon the closure of switches 3, the brushes 27, 28 and 29 are respectively connected with the remaining set of terminals 30, 31 and 32 of the secondary 65 phase-windings Sa, Sb and Sc, and the

phase-advancer armature is thus adapted to form a star-point in the secondary phase-winding system, while the liquid rheostat LR is connected to the set of terminals that are not associated with the phase-advancing armature. The phase-advancing machine may be brought up to speed and driven by any suitable auxiliary motor, as is customary practice, and no illustration or description of such driving means is believed necessary.

The switches 1 are merely adapted to short-circuit the liquid rheostat LR when they are closed, in accordance with a familiar practice.

Inasmuch as the particular type of governing system for manipulating the various switches in the desired sequence is immaterial to my present invention, I have not deemed it necessary to show or describe any such system. It will be understood that, in the case illustrated, a suitable master controller of a well-known type may readily be supplied by those skilled in the art to effect the circuit connections that are indicated in 85 Fig. 2. Moreover, if desired, a main-circuit controller having control fingers and conducting segments that correspond to the various switches that are shown in the figure may be utilized, if deemed preferable. Consequently, a sufficiently full and clear exposition of my invention is believed to be possible from a description of the main-circuit connections in conjunction with the sequence chart of Fig. 2.

Assuming that the primary winding P is connected to the supply-circuit conductors and that it is desired to effect acceleration of the induction motor, the operation may be set forth as follows: By initially closing the switches 2, the secondary phase-windings are connected in delta relation, while the phase-advancing machine PA is entirely excluded from circuit since the switches 3 are opened; and the height of the electrolyte in 100 the tank 10 of the liquid rheostat with respect to the electrodes 15 may be gradually varied in any suitable and well-known manner which it is not believed necessary to describe here. The motor is thus accelerated 105 with the secondary phase-winding connected in a low-starting-voltage combination that is suitable for operation with the liquid rheostat.

When full-speed conditions of the rotatable winding P have been attained, the switches 1 may be closed to short-circuit the liquid rheostat and also the secondary phase windings, an operation which takes place without any undesirable or injurious results to the induction motor, since the secondary or slip voltage thereof under full-speed conditions is relatively small, as will be understood.

To effect transition of the secondary phase

windings to the desired high-running-voltage combination; viz., star relation, the switches 3 are next closed, and then to permit phase regulation with the secondary 5 phase-windings in star-relation, the switches 2 are opened. The voltage between secondary phase-conductors is thus increased in the ratio of 1.73 to 1, by the change to star relation from the delta running relation that has 10 heretofore been used. If it is desired to concurrently effect phase-advancing and speed or slip regulation, the switches 1 may then also be opened, and such concurrent operation is permissible by reason of the fact that 15 the phase-advancing machine is connected to one corresponding set of terminals of the secondary phase winding, while the liquid rheostat is connected to the remaining terminals thereof, and, as will be understood, 20 only relatively low voltages will be impressed on the rheostat.

In the prior art, one objection to the use of a phase-advancer in connection with an induction motor has been the impracticality of concurrently employing a phase-advancing machine and a variable resistor for the customary function of regulating power-factor and speed conditions, respectively, in the induction motor, since the two 30 pieces of apparatus could be connected in parallel relation only. A system whereby concurrent use of the regulating devices in question is permitted, is shown and described and claimed in a co-pending application of 35 R. E. Hellmund, Serial No. 59,825, filed Nov. 5, 1915. In the application just mentioned, the relative location and connections of the phase-advancing machine and the variable resistor are similar to those herein 40 illustrated, whereby the desired concurrent phase-advancing and slip regulation is permitted.

The chief reason for desiring an independent speed regulation of driving induction 45 motors in electric locomotives, even during the period that phase-advancing machines are in operation, is the ability to compensate for unavoidable differences in the diameters of the driving wheels that are associated 50 with the various motors. As explained in the above-identified co-pending application, ordinarily, where the terminals of the secondary phase-windings are permanently connected, only one star-point is available and, 55 consequently, either the variable resistor or the phase-advancer alone can be inserted in the star-point; but by employing independent phase-windings, as in my present invention, both terminals of each phase-winding 60 may be employed, and thus, two star-points are available, whereby both a phase-advancing machine and a speed-regulating resistor may be concurrently operated. In the 65 above-specified co-pending application, the secondary winding of the induction motor

is disposed upon the rotor structure, as is customary, and, therefore, additional slip rings, with their consequent disadvantages, are necessary. By the use of my invention, however, the necessity for additional slip 70 rings is obviated, as already explained, because of the fact that I employ the primary winding as the rotatable member of the induction motor.

Referring now to Fig. 3, the system shown 75 comprises the supply-circuit conductors, the phase advancing machine and the liquid rheostat, as already described in connection with Fig. 1 and, in addition, an induction motor having a rotatable primary winding 80 P1 and a set S1 of independent stationary multi-section secondary phase-windings; and a plurality of sets of circuit-controlling switches 1, 11, 12, 13 and 14, respectively.

The primary winding P1 is similar in construction to the primary winding P of Fig. 1; whereas the secondary winding S1 comprises a plurality of star-related sets of phase-winding sections S1a and S1a', S1b and S1b' and S1c and S1c', respectively. 90 The switches 11 are respectively adapted to connect together the outer terminals of the phase-winding allied-sections; one of the switches 12 is adapted to connect the outer end of the phase winding section S1a to the 95 inner end of the section S1a', while the other switches 12 are similarly located with respect to the remaining sets of phase-winding sections; the switches 13 are collectively adapted to connect the inner terminals of the 100 phase-winding sections S1a', S1b', and S1c'; and the switches 14 are adapted to short-circuit the armature commutator cylinder 26 of the phase-advancing machine PA. The electrodes 15 of the liquid rheostat LR are 105 respectively connected through conductors 35, 36 and 37 to the outer terminals of the phase winding sections S1a', S1b' and S1c'. The brushes 27, 28 and 29 of the phase-advancing machine PA are respectively connected, through conductors 38, 39 and 40, to the inner terminals of the phase-winding sections S1b, S1a and S1c.

Assuming that the primary winding P1 is connected to the supply-circuit conductors 115 A, B and C and that it is desired to effect acceleration of the induction motor, the switches 11, 13 and 14 are initially closed, whereby the allied sections of the respective secondary phase-windings are connected in 120 parallel relation, and the phase-windings, as units, are connected in star-relation. By suitably manipulating the liquid rheostat LR, the induction motor may be gradually brought to full-speed in the relatively low- 125 starting-voltage, parallel-star relation just recited, the phase-advancing machine PA being meanwhile inoperative by reason of the closure of the switches 14.

When full-speed conditions have been at- 130

tained, the switches 1 may be closed for the familiar purpose of short-circuiting the liquid rheostat LR, while, to effect the desired transition of secondary winding connections to a high-running-voltage combination, the switches 12 may next be closed, thereby completely short-circuiting the secondary phase winding, which is permissible for the reason already explained.

10 To effect phase-advancing operation with the secondary phase winding in series-star relation, wherein the voltage between secondary phase-winding conductors is substantially doubled relative to the initial 15 parallel-star relation, the switches 11, 13 and 14 may then be opened, whereby the phase-advancing machine is operatively connected to the inner terminals of the phase-winding sections S1a, S1b and S1c, and the allied 20 sections of the respective secondary phase windings are disposed in series relation. For example, one circuit is completed from the brush 27 of the phase-advancer through conductor 38, phase-winding section S1b, one 25 of the switches 12, phase-winding section S1b' and conductor 36 to one of the electrodes 15 of the liquid rheostat. Similar connections obtain for the other secondary phase-windings.

30 If it is desired to concurrently effect phase-advancing and speed or slip regulation, the switches 1 may next be opened, whereby the liquid rheostat LR is connected to the outer set of terminals of the series- 35 related allied phase-winding sections, while the phase-advancing machine is connected to the remaining or inner set of terminals thereof, and thus the desired concurrent regulation is permitted.

40 Reference may now be had to Fig. 5, wherein the system shown comprises the supply-circuit conductors, the liquid rheostat LR, the phase-advancing machine PA and the primary and secondary induction 45 motor windings P1 and S1, as set forth in connection with Fig. 2 and, in addition, a second induction motor having a primary winding P2 that is similar in construction to the primary winding P1 and is suitably 50 mechanically associated therewith, as by a shaft or axle s, and a set S2 of stationary secondary phase-windings that are similar in construction and arrangement to the set S1 of phase-windings; a second liquid rheostat LR1; a plurality of sets of switches 1, 55 11, 11a, 12 and 13 that are associated with the set S1 of secondary phase-windings and the liquid rheostat LR; and a plurality of similar switches 21, 21a, 22, 23, 41 and 14 60 that are associated with the set S2 of secondary phase-windings, the liquid rheostat LR1 and the phase-advancing machine PA.

The switches 11 and 11a are respectively

adapted to connect the outer and the inner 65 terminals of the allied phase-winding sections; the switches 12 and 13 perform functions similar to those already described in connection with Fig. 2; the switches 21, 21a, 22 and 23 respectively correspond to switches 70 11, 11a, 12 and 13; the switches 41 are adapted to connect the liquid rheostat LR1 to the set S2 of secondary phase windings, while the switches 14 are adapted, upon the opening of switches 41, to cause the phase-advancer PA to replace the liquid rheostat LR1. 75

Assuming that the rotatable primary windings P1 and P2 are connected to the supply-circuit conductors and maintain identical 80 space-phase relations by reason of the mechanical interconnection, the acceleration of the induction motors may be effected by initially closing switches 11, 11a, 13, 21, 21a and 41, whereby each secondary winding is connected in star relation and with a resistor in circuit therewith. 85

The sets of secondary phase windings of the two induction motors are thus initially connected in series relation, considering that 90 the liquid rheostat tanks are in reality interconnected by reason of the usual practice of grounding such tanks, whereby a relatively low-voltage combination is employed in connection with liquid rheostat operation during the accelerating period. 95 However, in some cases, it may be advisable, when starting, to isolate the secondary windings to prevent possible double voltages on one rheostat, but, usually, the above-described series 100 relation is permissible.

When full-speed conditions have been attained by suitable manipulation of the liquid rheostats LR and LR1, switches 1 and 14 may be closed, whereby the respective 105 liquid rheostats are substantially short-circuited through the switches 1 alone and through the switches 14 and the relatively low-resistance armature windings of the phase-advancing machine PA, respectively. 110 To effect the desired transition of the motors from the lower-voltage, series-parallel-star combination, just described, to the desired new higher-voltage, series-star combination, the switches 12, 22 and 23 are first closed, 115 thereby short-circuiting all of the secondary phase-windings in accordance with the operation already mentioned, and switches 11, 11a, 13, 21, 21a, 23 and 41 are next opened. Consequently, one circuit is established from 120 one of the switches 1, through conductor 35, phase-winding section S1a', switch 12, phase-winding section S1a, conductor 45, phase-winding section S2a', switch 22, phase-winding section S2a, conductors 49 and 52 and 125 switch 14 to one of the brushes of the phase-advancing machine PA. Similar circuits obtain for the remaining groups of correspond-

ing secondary phase-windings, and it is not believed to be necessary to trace such circuits in detail. It should be observed that, by the closure of the switches 14 and subsequent opening of switches 41, the phase-advancing machine PA replaces the liquid rheostat LR1, the respective brushes of the phase-advancing machine being connected through conductors 51, 52 and 53 to the conductors 50, 49 and 48. Phase-regulating operation is thus effected with the secondary phase-windings connected in a relatively high-running-voltage combination, whereby a still further reduction of current and corresponding increase of voltage during the phase-advancing period may be accomplished.

If it is desired to effect concurrent phase-advancing and slip regulation, the switch 1 may be opened, whereby the liquid rheostat LR is associated with one set of terminals of the above-outlined series phase-winding circuits, while the phase-advancing machine PA is connected to the other terminals of such circuits, and the desired concurrent operation may be accomplished in a manner similar to that set forth in connection with the other systems.

It should be noted that the system just described may be readily adapted to permit cascade operation of a plurality of induction motors, if such operation is desired in conjunction with the use of my present invention.

I have thus provided a number of induction motor systems wherein relatively low-starting-voltage combinations are employed in conjunction with variable resistors having low-voltage characteristics during the accelerating period, and, after the motors have been accelerated to full-speed conditions, the terminals of the secondary phase windings are indiscriminately short-circuited and then opened at the points which afford the desired reconnection that corresponds to the high-running-voltage, lower-current combination, whereby a phase-advancing machine may be more economically operated for the usual regulating purposes. Moreover, the concurrent use of speed-regulating means and phase-regulating means is permitted in a relatively simple and inexpensive manner by the use of my invention.

I do not wish to be restricted to the specific circuit connections or location and arrangement of parts herein set forth, as, obviously, various modifications thereof may be made without departing from the spirit and scope of my invention. I desire, therefore, that only such limitations shall be imposed as are indicated in the appended claims.

I claim as my invention:

1. In a system of control, the combination with a supply circuit, of an induction motor having a primary winding and a plurality of independent secondary phase windings, a variable resistor, a polyphase commutator machine, means for initially connecting said phase windings in delta relation, means for employing said variable resistor in circuit with said phase windings to effect acceleration of the motor, means for reconnecting said phase windings in star relation for operation under full-speed conditions, and means for connecting said commutator machine to said reconnected phase windings. 65 70 75

2. In a system of control, the combination with a supply circuit, of an induction motor having a primary winding and a plurality of independent secondary phase windings, 80 a variable resistor, a phase-advancing machine, means for initially connecting said phase windings in delta relation, means for connecting said variable resistor in circuit with said phase windings to effect acceleration of the motor, means for reconnecting said phase windings in star relation for operation under full-speed conditions, and means for connecting said phase-advancing machine to the phase-winding terminals not 90 connected to said variable resistor, whereby power-factor and speed regulation of the induction motor may be independently obtained. 95

3. The method of operating an induction motor having a primary winding and a plurality of secondary phase windings in conjunction with speed-regulating means and phase-regulating means that consists in employing said speed-regulating means to accelerate the motor with a relatively low-voltage arrangement of the phase windings and subsequently rearranging said phase windings in a higher-voltage combination and employing said phase-regulating means. 100 105

4. The method of operating an induction motor having a primary winding and a plurality of secondary phase windings in conjunction with a variable resistor and a phase-advancing machine that consists in employing said variable resistor to accelerate the motor with the phase windings arranged in delta relation, short-circuiting said phase windings when full-speed conditions are attained, rearranging the phase windings in star relation and employing said phase advancing machine. 110 115

In testimony whereof, I have hereunto subscribed my name this 31st day of Jan., 1916.

STANLEY G. NOTTAGE.
